Primary Examiner — Mark A Goodwin*(74) Attorney, Agent, or Firm* — Tucker Ellis LLP; Carlos Garritano(57) **CLAIM**

The ornamental design for an injection lance attachment, as shown and described.

DESCRIPTION

FIG. 1 is a top perspective view of an injection lance attachment showing our new design;

FIG. 2 is a bottom perspective of the injection lance attachment illustrated in FIG. 1;

FIG. 3 is a top view of the injection lance attachment illustrated in FIG. 1;

FIG. 4 is a bottom view of the injection lance attachment illustrated in FIG. 1;

FIG. 5 is a left side view of the injection lance attachment illustrated in FIG. 1;

FIG. 6 is a right side view of the injection lance attachment illustrated in FIG. 1;

FIG. 7 is a rear view of the injection lance attachment illustrated in FIG. 1; and,

FIG. 8 is a front view of the injection lance attachment illustrated in FIG. 1.

The broken lines in the drawings illustrate the portions of the injection lance attachment that form no part of the claimed design. The break lines represent sections of the injection lance attachment of indeterminate length.

1 Claim, 5 Drawing Sheets(56)
